UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING MACHINE.

Application filed June 13, 1921. Serial No. 477,043.

To all whom it may concern:

Be it known that I, MORRIS P. HOLMES, a citizen of the United States, residing at Claremont, in the county of Sullivan and State of New Hampshire, have invented certain new and useful Improvements in Mining Machines, of which the following is a full, clear, and exact specification.

My invention relates to mining machines. 10 It has for its object to provide an improved feeding mechanism for a mining machine. A further object of my invention is to provide an improved feeding mechanism utilizing a flexible feeding member, and especially adapted to use in connection with a feeding member formed of cable, this mechanism being improved in such a manner that even when a cable is used as the feeding member, certain advantages of the well known chain feed may be obtained. These and other objects and advantages of my invention will, however, hereinafter more fully appear.

In the accompanying drawings I have shown for purposes of illustration one embodiment which my invention may assume in practice.

In these drawings,— Fig. 1 is a plan view of a machine 30 equipped with my improvement.

Fig. 2 is a side elevation of the same, the take-up mechanism being shown in a plurality of positions.

Fig. 3 is a diagrammatic view showing the machine making its sumping and transverse cuts at the face.

In this illustrative construction, I have shown a machine of a usual room and pillar type including a frame 1 slidable over the mine bottom and having a forwardly projecting cutter bar 2 thereon carrying a cutter chain 3, the cutter chain being driven in a usual manner from a motor 4 on the frame through mechanism not shown.

In my improved construction, flexible feeding means in the form of preferably a continuous length of a flexible member, herein a cable 6, is utilized, the cable being extended forward around an idler sheave 7 herein disposed in a horizontal plane and located at the front end of the frame, and being extended rearward around

cooperating idler sheaves 8 and 9, herein disposed in a single plane slightly inclined to the horizontal and located at the rear 55 end of the frame. As shown, the motor 4 is connected through suitable reversible gearing 10 to a transversely disposed shaft 11 herein located substantially midway between the ends of the frame and extending laterally beyond one side of the frame. This shaft, in turn, carries on its end a feed operating member, herein a drum 12, grooved, as at 13, to receive a plurality of strands of cable. Operatively associated 60 with this drum 12, is also an idler drum 14 similarly grooved at 15 and located in rear, and herein slightly above, the drum 12, the drum 14 being freely rotatable on a stud 16 likewise extending laterally from the same 65 side of the frame, and both the drums 12 and 14 being removably attached to their shafts and studs, respectively, by means of washer and screw connections 17. As illustrated, it will be observed that the cable 70 6 extends from the idler 7 rearward of and along the side of the frame and is brought in under a cooperating idler 18 herein disposed beneath the drums and substantially midway between the same. From 75 this idler 18 the cable is then preferably brought upward and around the innermost groove on the drum 14, and then passed over the innermost groove on the drum 12, the same thereafter passing back and forth under the drums 12 and 14 and over the same as shown until all the grooves are 80 filled, when the cable leaves the outer groove of the drum 12, herein from the bottom of the drum, and is directed rearward of the frame to the idler 8 and passed therearound and by the idler 9 rearward relative to the moving machine. Cooperating with the cable, as shown herein, is also a take-up, 85 herein in the form of an adjustable idler 19. This idler is herein carried on a suitable sliding and preferably weighted block 20 movable freely in a slot 21 which is in turn formed in the side of the frame 1 between the drums 12 and 14 and disposed at right angles to the plane passing through the axes of the drums. As shown, this idler 95 19 is disposed above the last or outermost strand which passes over the drums 12 and 100

14, and is adapted to take up the slack in that strand when desired and to be adjusted into any desired position by means of a handle, herein in the form of a winged nut 5 22 carried on the block and adapted to engage with the frame and to hold the idler in any desired position, the construction being such that through the reversible drum drive and the adjustable take-up, any desired angular variation of the machine may 10 be obtained when the latter moves between the oppositely extending ends of the cable fixed to suitable jacks 23, 24.

In the operation of the construction 15 shown, it will be evident that, as shown in Fig. 3, the machine may be dumped into the face by passing the rear end of the cable around the idlers 8 and 9, and connecting the same to a jack 23 disposed at the right 20 hand rib, the machine moving relative to the cable, and along the same into the coal when the power drum is rotated. It will also be observed that after the machine has thus been dumped into the coal, by simply 25 changing the connection of the jack at the right hand rib so that it occupies the dotted position at the rear of the machine shown in Fig. 3, and connecting the front or forward end of the cable to a jack 24 at the left hand 30 rib and closely adjacent the face of the coal, it is possible for the machine to move transversely along the face in a well known manner. During these operations it will also be 35 particularly observed that whenever it is desired to angle the machine, this may be accomplished by varying the position of the adjustable take-up or idler 19, the same being adjustable in its slot to take up any slack, and adapted to be held in a definite 40 position in its slot by the winged nut 22 when such a relation of the parts is desired.

In the use of my improved construction, it 45 will be observed that it is possible to develop a decided friction on a cable through the use of the drums and the multiple convolutions of cable thereon, and thereby develop the pull required, a cable in my improved construction being adapted to exert a pull of six thousand or more pounds, as 50 needed. It will also be observed that in my improved construction the necessity for a take-up distinct from the machine is entirely eliminated, the reversible drum drive serving to insert slack when desired, while 55 the take-up mechanism is adapted to act upon any slack which may be inserted for any reason in the cable in such a manner as to enable the position or movement of the machine to be controlled as desired. At the 60 same time it will be observed that the mechanism required is of an exceedingly simple character and adapted to be manufactured at small expense and, if desired, applied to standard machines. These and other advantages of my improved construction will,

however, be clearly apparent to those skilled in the art.

While I have in this application specifically described one embodiment which my invention may assume in practice, it will 70 be understood that this form is shown for illustrative purposes, and that the invention may be modified and embodied in various other forms without departing from its spirit or the scope of the appended claims. 75

What I claim as new and desire to secure by Letters Patent is:

1. The combination with a mining machine having a frame slideable on its bottom over a mine bottom during cutting, of 80 flexible machine feeding and guiding mechanism therefor including a continuous flexible feeding member extending in opposite directions from points at the opposite ends of said machine, and a plurality of winding drums between said points rotatable on parallel axes and around which the intermediate portion of said member is wound in loops each of which passes around all of 85 said drums. 90

2. The combination with a mining machine including a frame slideable on its bottom on a mine bottom during cutting, of 95 flexible feeding and machine guiding means adapted to position said machine during cutting including a single flexible feed cable extending in opposite directions from points at the opposite ends of said machine, and feed operating means therefor including a plurality of drums disposed on parallel 100 transverse axes and located between said points.

3. The combination with a mining machine slideable on a mine bottom, of a single flexible feed cable extending in opposite 105 directions from points at the opposite ends of said machine, and feed operating means therefor including a plurality of adjacent drums disposed on parallel relatively fixed axes and located between said points and on 110 the same side of said machine.

4. The combination with a mining machine slideable on a mine bottom, of a single flexible feed cable extending in opposite directions from points at the opposite ends of 115 said machine, and feed operating means therefor including a feed operating drum and an idler drum disposed on fixed parallel axes on the advancing side of said machine. 120

5. The combination with a mining machine slideable on a mine bottom, of a continuous flexible feeding member extending in opposite directions from points at the opposite ends thereof, and feed operating 125 means disposed between said points including a plurality of drums located on fixed transverse axes on the advancing side of the machine around a portion of each of which said member is successively wound. 120

6. The combination with a mining machine slideable on a mine bottom, of a flexible feeding member extending in opposite directions from points at the opposite ends of said machine, feed operating means therefor including a plurality of drums between said points both of which lie within at least one single loop of said flexible feeding member, and a take-up acting on said member at a point between said drums. 10
7. The combination with a mining machine slideable on a mine bottom, of a flexible feeding member extending in opposite directions from points at the opposite ends of said machine, feed operating means therefor including a plurality of drums between said points and on the same side of said machine, and a take-up between said drums acting on said member at a point between said drums. 20
8. The combination with a mining machine, of a flexible feeding member extending in opposite directions from points at the opposite ends of said machine, a plurality of winding drums located between said points and upon which said member is wound in such manner that a plurality of loops are formed in each of which both drums lie, and a take-up member engageable with said flexible member. 30
9. The combination with a mining machine slideable on a mine bottom, of a flexible feeding member extending in opposite directions from points at the opposite ends of said machine, a plurality of winding drums located between said points and upon which said member is wound in such manner that both drums are included in at least one common loop, and a take-up member engageable with said flexible member at a point between said drums. 40
10. The combination with a mining machine slideable on its bottom on a mine bottom during cutting, of a flexible machine feeding and guiding member extending in opposite directions from points at opposite ends of said machine, a plurality of winding drums located between said points and upon which said member is wound, both drums being included in a single complete wrap of said flexible member, and a take-up member engageable with said flexible member at a point between said drums. 50
11. The combination with a mining machine slideable on a mine bottom, of a flexible feeding member extending in opposite directions from points at the opposite ends of said machine, feed operating means therefor including a plurality of drums around which the intermediate portion of said member is wound, both drums being included in a single complete wrap of said flexible feeding member, and a take-up acting on a single strand of said member at a point between said drums. 60
12. The combination with a mining machine slideable on a mine bottom, of a single flexible feed cable extending in opposite directions from points at the opposite ends of said machine, feed operating means therefor including a plurality of drums disposed on parallel axes between said points, and a take-up mechanism operative upon said cable as it passes between said drums. 70
13. The combination with a mining machine slideable on a mine bottom, of a single flexible feed cable extending in opposite directions from points at the opposite ends of said machine, feed operating means engaging therewith including a plurality of drums disposed on parallel axes between said points, and take-up mechanism acting upon the last strand of cable passing between said drums. 75
14. The combination with a mining machine slideable on a mine bottom, of a single flexible feed cable extending in opposite directions from points at the opposite ends of said machine, feed operating means therefor including a plurality of drums disposed on parallel axes between said points, take-up mechanism acting upon said cable at a point between said drums, and means for adjusting said take-up. 80
15. The combination with a mining machine slideable on a mine bottom, of a single flexible feed cable extending in opposite directions from points at the opposite ends of said machine, feed operating means therefor including a plurality of drums disposed on parallel axes between said points, and a weighted take-up mechanism operative upon said cable as it passes between said drums. 85
16. The combination with a mining machine slideable on a mine bottom, of a single flexible feed cable extending in opposite directions from points at the opposite ends of said machine, feed operating means therefor including a plurality of drums disposed on parallel axes between said points, take-up mechanism acting upon said cable as it passes between said drums, and means for holding the same in one of a plurality of positions on said frame. 90
17. The combination with a mining machine slideable on a mine bottom, of a flexible feeding member extending in opposite directions from points at the opposite ends thereof, and feed operating means including a plurality of drums between said points upon which said member is wound in such manner that a plurality of loops are formed in each of which both drums lie, said member having its free ends passing off from beneath different drums. 105
18. The combination with a mining machine slideable on a mine bottom, of a flexible feeding member extending in opposite directions from points at the opposite ends thereof, feed operating means including a 110
19. The combination with a mining machine slideable on a mine bottom, of a flexible feeding member extending in opposite directions from points at the opposite ends thereof, feed operating means including a 115
20. The combination with a mining machine slideable on a mine bottom, of a flexible feeding member extending in opposite directions from points at the opposite ends thereof, feed operating means including a 120
21. The combination with a mining machine slideable on a mine bottom, of a flexible feeding member extending in opposite directions from points at the opposite ends thereof, feed operating means including a 125
22. The combination with a mining machine slideable on a mine bottom, of a flexible feeding member extending in opposite directions from points at the opposite ends thereof, feed operating means including a 130

plurality of drums between said points upon which said member is wound in such manner that a plurality of loops are formed in each of which both drums lie, and power means for rotating one of said drums.

19. The combination with a mining machine slideable on a mine bottom, of a flexible feeding member extending in opposite directions from points at the opposite ends thereof, feed operating means including a plurality of drums between said points upon which said member is wound in such manner that a plurality of loops are formed in each of which both drums lie, and power means for rotating one of said drums in opposite directions.

20. The combination with a mining machine slideable on a mine bottom, of a flexible feeding member extending in opposite directions from points at the opposite ends thereof, feed operating means including a plurality of drums between said points upon which said member is wound in such manner that a plurality of loops are formed in each of which both drums lie, and power means for rotating one of said drums at different speeds.

21. The combination with a mining machine slideable on a mine bottom, of a flexible feeding member extending in opposite directions from points at the opposite ends thereof, feed operating means including a plurality of drums between said points upon which said member is wound in such manner that a plurality of loops are formed in each of which both drums lie, and power means for rotating one of said drums in opposite directions at different speeds.

22. The combination with a mining machine slideable on a mine bottom, of a continuous cable extending in opposite directions from opposite ends thereof, and feed operating means operative to draw in either end thereof comprising a plurality of drums rotatable on parallel axes extending horizontally from said machine in the same direction, said drums having the intermediate portion of said cable wound around both drums.

23. The combination with a mining machine slideable on a mine bottom, of a continuous cable extending in opposite directions from opposite ends thereof, and feed operating means operative to draw in either end thereof comprising a plurality of adjacent drums rotatable on parallel axes and having the intermediate portion of said cable wound around both drums and the free ends of said cable passing off from the under side of different drums.

24. The combination with a mining machine slideable on a mine bottom, of a continuous cable disposable in advance and receding portions from opposite ends thereof, feed operating means operative to draw in

either end thereof comprising a plurality of drums rotatable on parallel axes and having the intermediate portion of said cable wound around both drums, and a take-up operable on one of the strands of said cable passing between said drums.

25. The combination with a mining machine slideable on a mine bottom, of a continuous cable disposable in advance and receding portions from opposite ends thereof, feed operating means operative to draw in either end thereof comprising a plurality of drums rotatable on parallel axes and having the intermediate portion of said cable wound around both drums, and a take-up operable on the last strand of said cable passing between said drums and leading to said receding portion.

26. The combination with a mining machine slideable on a mine bottom, of flexible lateral feeding means including flexible feeding portions disposable in opposite directions from opposite ends of said machine and feed operating and take-up mechanism disposed on the advancing side of said machine operative to produce lateral feeding and to vary the length of either portion at will and including a plurality of drums.

27. The combination with a mining machine slideable on a mine bottom, of flexible lateral feeding means including flexible feeding portions disposable in opposite directions from opposite ends of said machine and feed operating and take-up mechanism disposed on the advancing side of said machine operative to produce lateral feeding and to vary the length of either portion at will including a plurality of drums rotatable on transversely disposed axes.

28. The combination with a mining machine slideable on a mine bottom, of flexible lateral feeding means including a continuous flexible feeding member having flexible feeding portions disposable in opposite directions from opposite ends of said machine and feed operating and take-up mechanism disposed on the advancing side of said machine operative to produce lateral feeding and to vary the length of either portion at will including a plurality of drums rotatable on transversely disposed parallel axes.

29. The combination with a mining machine slideable on a mine bottom, of a continuous cable disposable in advance and receding portions from opposite ends thereof, feed operating means operative to draw in either end thereof comprising a plurality of drums rotatable on parallel axes and having the intermediate portion of said cable wound around both drums in such manner that both drums are engaged by each complete wrap of cable, and a take-up operable on one of the strands of said cable passing between said drums.

30. The combination with a mining ma-

chine slideable during cutting on its bottom on a mine bottom, of flexible feeding and machine guiding means including a continuous cable disposed during cutting across a 5 face in advance and receding portions from opposite ends thereof, feed operating means operative to draw in either end thereof com-

prising a plurality of drums rotatable on parallel axes and having the intermediate portion of the cable wound on both drums, 10 and a take-up member adjustable to cut the plane including the axes of said drums.

In testimony whereof I affix my signature.

MORRIS P. HOLMES.

• **Certificate of Correction.**

It is hereby certified that in Letters Patent No. 1,533,316, granted April 14, 1925, upon the application of Morris P. Holmes, of Claremont, New Hampshire, for an improvement in "Mining Machines," errors appear in the printed specification requiring correction as follows: Page 2, line 100, claim 2, before the word "drums" insert the word *adjacent*, and line 108, claim 3, strike out the word "adjacent"; and that the said Letters Patent should be read with these corrections therein that the same may conform to the record of the case in the Patent Office.

Signed and sealed this 16th day of June, A. D. 1925.

[SEAL.]

KARL FENNING,
Acting Commissioner of Patents.
